HEAT RECOVERY

Application filed November 1, 1928. Serial No. 316,499.

My invention relates to heat recovery and has for its principal object to recover the waste heat in liquor discharged from a pulp digester. In a number of processes, particularly in connection with paper mills in which old paper stock is de-inked, the paper stock is heated to a high temperature in a relatively large amount of water and is digested for a considerable period at the high temperature. 5 When the digesting is over, it is customary to conduct the pulp to the next stage in the process and dissipate the heat of the pulp liquor. I propose to make use of this heat as it is of appreciable amount. 10 In my method of recovering the heat I propose to use the principle of flashing steam by lowering the pressure of hot water. The steam thus produced is pure and can be used in a number of ways. I prefer to use it for 15 heating fresh water and I accomplish this in a multi-stage evaporator system.

My invention will be further explained by reference to the accompanying drawings showing parts of a plant for carrying out 20 the invention and whereon:

Fig. 1 shows one arrangement of apparatus for carrying out the invention;

Fig. 2 is a side view of the arrangement shown in Fig. 1; and

Fig. 3 is a view at right angles to Fig. 2 showing a loop in a connection between condensers.

Reference character 10 designates a digester for digesting pulp. It may be a sulphite or sulphate or old paper stock digester. After a cook the digester discharges pulp liquor. The liquor discharged may be waste liquor, the pulp being separated or it may contain the pulp. The pulp liquor is conducted through conduit 11 to first stage evaporator 12. The evaporator may be of any various known types of construction. This evaporator is maintained at a low absolute pressure, for example, about 5 inches 40 of mercury absolute. This low absolute pressure of vacuum is maintained by first stage condenser 13 connected to the evaporator by conduit 14. Vacuum pump 15 withdraws gas from condenser 13 and tail pump 16 with- 45 draws condensate.

The temperature of the pulp liquor entering first stage evaporator 12 will have a temperature of, let us say, 170° F. In view of the low pressure, some of the water of the liquor flashes into steam. As steam is 55 formed the temperature drops in order to supply the latent heat of evaporation until a liquor temperature is reached which corresponds to the pressure of about 5 inches of mercury, which is about 135° F. The flash 60 steam formed in this stage passes through conduit 14 and is condensed in condenser 13. In condensing it gives up heat to and heats fresh water supplied to condenser 13 through conduit 17. The water heated and the steam 65 to be condensed are in direct contact in condenser 13 and the resultant hot water passes out through conduit 18 and is forced by pump 16 to the point of use which may be a different digester about to be heated. 70

About 5% of the water of the pulp liquor is evaporated in evaporator 12. The remaining pulp liquor passes through pipe 19, which is arranged to provide a sealing loop, and into second stage evaporator 20. Second 75 stage evaporator 20 is at a lower level than first stage evaporator 12 to permit the liquor to flow by gravity from the latter to the former.

In the second stage evaporator 20, a still 80 lower pressure is maintained, let us say 1.5 inches of mercury absolute. The corresponding boiling point of water is about 90° F. The liquor entering the second stage evaporator 20 has a temperature of about 135° F., determined by the pressure in first stage evaporator 12. Consequently, the temperature being above the boiling point, steam flashes in the second stage evaporator, the temperature 85 lowering to or toward 90° F. 90

Evaporator 20 is equipped with a cone baffle 30 for distributing the liquor. Evaporator 12 is preferably equipped with a similar baffle.

The steam formed in evaporator 20 passes 95 through conduit 21 and into second stage condenser 22. Condenser 22 receives the fresh water to be heated through inlet 23. The cold water and steam mix and the resulting hot water passes out through conduit 100

17 and into first stage condenser 13 where it is further heated, as above explained due to the higher temperature of steam supplied to condenser 13.

5 The lower pressure in second stage evaporator 20 is maintained by condenser 22. Condenser 22 can produce a lower pressure because the temperature of cooling water is lower in condenser 22 than in condenser 13.

10 Non-condensable gas, together with some steam, is withdrawn from condenser 22 by pump 24 and passes into condenser 13 through conduits 25 and 14. Pumps 15 and 24 are preferably steam jet pumps supplied with

15 steam from any suitable source. The steam supplied to pump 24 is condensed in condenser 13. The steam supplied to pump 15 is condensed in an after-condenser 26 through which the hot water discharged by pump 16

20 passes. The heat of the steam used to operate pumps 15 and 24 is thus completely recovered.

The height of condenser 22 above condenser 13 and consequently the unbalanced

25 liquid column in pipe 17 serves to permit the higher pressure in condenser 13 than in condenser 22. The arrangement also facilitates flow by gravity from condenser 22 to condenser 13.

30 The loop in pipe 19 should be sufficiently long or have sufficient resistance so that the higher pressure in evaporator 12 will not empty the loop but maintain a seal permitting the different pressures to exist in the

35 evaporators.

The liquor leaves evaporator 20 through pipe 28 and pump 29.

The measure of heat recovery is the quantity of water passing through pump 16 multiplied by the difference in temperature between the resultant hot water and the cold supply water.

40 It will be understood that the values of temperature and pressure given are for illustrative purposes only. These are approximately the temperatures and pressures existing in one plant equipped with the present invention.

45 While I have shown the invention as applied to the heating of fresh water, it will be understood that the flash steam may be used to heat other fluids or substances. Furthermore, while I have illustrated and described a two stage evaporator system it will be obvious that one or three or more stage or stages may be used. Essentially, what I have provided in the described embodiment is a plurality of evaporators arranged in series in each of which steam is flashed and a plurality of water heaters arranged in series through which a stream of fresh water flows and cross-connections conducting the flashed steam into the water heaters in inverse relation to flow; that is, so that the steam first flashed goes to 55 the last water heater in line of flow. I do not

limit myself to any specific type of evaporator or condenser.

It will be seen that my process of heat recovery is continuous.

What I claim is:

1. The process of recovering heat from hot pulp liquor discharged from a digester which comprises successively lowering the pressure and the temperature of the hot pulp liquor and flashing steam therefrom at different 75 temperatures, and producing flow of and progressively increasing the temperature and the pressure of water in direct contact with the flashed steam of different temperatures.

2. The process of recovering heat from hot liquid carrying material in suspension which comprises successively lowering the pressure and the temperature of the liquid and flashing steam therefrom at different temperatures, conducting water in direct contact with the flashed steam of different temperatures and progressively increasing the temperature and the pressure of the water.

3. The process of recovering heat from hot pulp liquor discharged from a digester which comprises successively lowering the pressure and the temperature of the hot pulp liquor and flashing steam therefrom at different 90 temperatures, producing flow of and progressively increasing the temperature and the pressure of water in direct contact with the flashed steam of different temperatures, balancing the pressure drop in the pulp liquor by a hydrostatic column and utilizing a hydrostatic column to produce the rise in pressure 95 of the water.

4. The process of recovering heat from liquid carrying material in suspension which comprises successively lowering the pressure 105 and the temperature of the liquid and flashing steam therefrom at different temperatures, producing flow of and progressively increasing the temperature and the pressure of fresh water in direct contact with the flashed steam of different temperatures, balancing the pressure drop in the liquid having material in suspension by a hydrostatic column and utilizing a second hydrostatic column to produce the rise in pressure of the 110 fresh water.

5. Apparatus of the character set forth for treating pulp liquor and the like comprising a first evaporator, a second evaporator, a first condenser, a second condenser, a vapor connection between the first evaporator and the first condenser, a vapor connection between the second evaporator and the second condenser, means for conducting liquid from the first evaporator to the second evaporator and liquid from the second condenser to the first condenser and for maintaining a higher pressure in the first evaporator and first condenser than in the second evaporator and second condenser comprising a connecting con- 125

duit between the first evaporator and the second evaporator adapted to hold a hydrostatic column of liquid and a connecting conduit between the second condenser and the 5 first condenser adapted to hold a hydrostatic column of liquid, means to supply liquor to be treated to the first evaporator, means to withdraw treated liquor from the second evaporator, means to supply cold water to the 10 second condenser and means to withdraw water from the first condenser.

6. Apparatus of the character set forth for treating pulp liquor and the like comprising a first evaporator, a second evaporator, a first condenser, a second condenser, a vapor connection between the first evaporator and the first condenser, a vapor connection between the second evaporator and the second condenser, means for conducting liquid from the 15 first evaporator to the second evaporator and liquid from the second condenser to the first condenser and for maintaining a higher pressure in the first evaporator and first condenser than in the second evaporator and second condenser comprising an unrestricted relatively large connecting conduit between the first evaporator and the second evaporator adapted to hold a hydrostatic column of liquid and a connecting conduit between the 20 second condenser and the first condenser adapted to hold a hydrostatic column of liquid, means to supply liquor to be treated to the first evaporator, means to withdraw treated liquor from the second evaporator, means to supply cold water to the second condenser and means to withdraw water from the first condenser.

7. Apparatus of the character set forth for treating pulp liquor and the like comprising a first evaporator, a second evaporator, a first condenser, a second condenser, a vapor connection between the first evaporator and the first condenser, a vapor connection between the second evaporator and the second condenser, means for conducting liquid from the first evaporator to the second evaporator and liquid from the second condenser to the first condenser and for maintaining a higher pressure in the first 45 evaporator and first condenser than in the second evaporator and second condenser comprising an unrestricted connecting conduit forming a U-loop seal between the first evaporator adapted to hold a hydrostatic column of liquid and a connecting conduit between the second condenser and the first condenser adapted to hold a hydrostatic column of liquid, means to supply liquor to be treated to the first evaporator, means to withdraw treated liquor from the second evaporator, means to supply cold water to the second condenser and means to withdraw water from the first condenser.

8. Apparatus of the character set forth for 60 treating pulp liquor and the like comprising

a first evaporator, a second evaporator, a first condenser, a second condenser, a vapor connection between the first evaporator and the first condenser, a vapor connection between the second evaporator and the second condenser, means for conducting liquid from the first evaporator to the second evaporator and liquid from the second condenser to the first condenser and for maintaining a higher pressure in the first evaporator and first condenser than in the second evaporator and second condenser comprising a relatively large unrestricted connecting conduit forming a loop between the first evaporator and the second evaporator and adapted to hold a hydrostatic column of liquid and a connecting conduit between the second condenser and the first condenser adapted to hold a hydrostatic column of liquid, means to supply liquor to be treated to the first evaporator, means to withdraw treated liquor from the second evaporator, means to supply cold water to the second condenser and means to withdraw water from the first condenser.

9. The process of recovering heat from hot pulp liquor discharged from a digester which comprises successively lowering the pressure and the temperature of the hot pulp liquor and flashing steam therefrom at different temperatures, producing flow of and progressively increasing the temperature and the pressure of water in direct contact with the flashed steam of different temperatures, and balancing the pressure drop in the pulp liquor by a hydrostatic column.

10. Apparatus of the character set forth for treating pulp liquor and the like comprising a first evaporator, a second evaporator, a first condenser, a second condenser, a vapor connection between the first evaporator and the first condenser, a vapor connection between the second evaporator and the second condenser, means for conducting liquid from the first evaporator to the second evaporator and liquid from the second condenser to the first condenser and for maintaining a higher pressure in the first evaporator and first condenser than in the second evaporator and second condenser comprising a connecting conduit between the first evaporator and the second evaporator adapted to hold a hydrostatic column of liquid, means to supply liquor to be treated to the first evaporator, means to withdraw treated liquor from the second evaporator, means to supply cold water to the second condenser, and means to withdraw water from the first condenser.
